UNITED STATES PATENT OFFICE.

GEORGE A. WHITE, OF BRISTOL, CONNECTICUT.

GAME-TABLE.

SPECIFICATION forming part of Letters Patent No. 735,186, dated August 4, 1903.

Application filed November 25, 1901. Serial No. 83,650. (No model.)

To all whom it may concern:

Be it known that I, GEORGE A. WHITE, a citizen of the United States, residing at Bristol, in the county of Hartford and State of Connecticut, have invented certain new and useful Improvements in Game - Tables, of which the following is a specification.

My invention relates to improvements in game-tables, and the main object of my improvement is to make the game simple and attractive.

In the accompanying drawings, Figure 1 is a plan view of my game-table. Fig. 2 is a longitudinal section of the main portion of the same on the line *x x* of Fig. 1. Fig. 3 is a transverse section on the line *y y* of Fig. 1, and Fig. 4 is a detached front elevation of one of the banner-tablets belonging to my game-table.

20 A designates the table, supported upon any suitable support or legs 5 of its own or placed upon the top of any ordinary table, as may be desired. The top of my table is in three sections—a horizontal portion 6 at the lower 25 end, an intermediate inclined portion 7, and an upper inclined portion 8 of less inclination than the intermediate portion 7. Both of the end portions 6 and 8 are rounded and provided with guards or wards 9 10 to avoid 30 angular corners and to direct the balls on their return movement. At the lower end is a central ward or deflector 11 to prevent the ball from following closely the guard 9. The lower end or horizontal portion 6 of the table- 35 top has a series of numbered pockets 12, which may be given any desired numbers, preferably numbered substantially as shown, with proportionately higher numbers on the pockets that are the least likely to have a ball 40 lodge in them. At one side of the table there is a guard or ward 13, extending from bottom to top of the middle inclined portion 7 and forming with the side guard 14 on that side a trough or passage-way for shooting a ball 45 of any desired kind—as, for example, a ball of somewhat yielding material, like those used for base-ball, or of solid unyielding material, like the balls used in billiards. Across the table near the junction of the portions 7 50 and 8 I arrange a series of pins 15, separated from each other a little more than the diameter of the balls to be employed, and between

most of the said pins I have swinging banner-tablets 16, pivoted to the said pins by means of trunnions 17, Fig. 4, at their upper ends, so that when a ball coming from above strikes the said tablets they may swing on their trunnions and let the ball pass downwardly between the pins 15. In order to prevent the balls from rolling directly down toward the lower end after passing one of the banner-tablets, I arrange a staggered series of pins 18 on the middle inclined portion 7 of the table to compel the ball to travel in a zigzag course in passing down the incline. 60 Two pins 19 in this series are pivoted to the table by a pin 20, Fig. 2, so that they may swing downwardly under the force of the ball which strikes them, and underneath the table I hang a bell 21, connected by a wire or 65 rod 22 to the lower end of the pin 19, whereby whenever either one of the pins 19 is hit by a ball the bell will ring. At the central space between the pins 15 I omit the swinging or banner tablet and in the table make 70 a slight pocket or ball-seat 23, upon which to set a spot-ball. At any convenient place adjacent to the lower end of the main ball-passage I arrange a cue-rest 24 of any ordinary construction. The banner-tablets may be 75 given any desired numbers; but I prefer to give the highest numbers to the middle tablets, as they are comparatively harder to hit than the tablets nearer the sides of the table.

In playing the game a spot-ball is placed 80 on the seat or pocket 23 and a ball is shot upwardly in the ball-passage by means of a billiard-cue. If the ball fails to pass through the said passage to the upper end portion 8 of the table, it will roll downwardly to the 85 lower horizontal portion 6. If it comes to rest outside of any of the pockets 12, it counts nothing, but if it rests in any one of the said pockets it counts whatever the number of that pocket may be. If the ball passes through 90 the ball-passage to the upper portion 8 of the table, it will roll downwardly and must pass between the pins 15. If it strikes and deflects one of the banner-tablets, it counts the number marked on the said tablet. If it strikes 95 the spot-ball in the seat or socket 23 and starts the said ball out of said seat, both of the balls roll downwardly, and if either of them hits one of the pins 19 and rings the bell it counts 100

the number given to the said bell-pins, and at the lower end both balls count according to the number of the pockets in which they may come to rest.

5. I claim as my improvement--

1. A game-table having a lower horizontal face with a series of numbered ball-pockets sunk below the said face, a middle inclined face with a series of staggered pins distributed over and projecting from the said face, and an upper inclined face slanting in the same direction as the said middle inclined face, but at a lesser angle of inclination, substantially as described.
10. 2. A game-table having an inclined middle face with a series of staggered pins distributed over the said face and projecting upwardly therefrom, an upper table-face at a less angle of inclination, a spot-ball seat and a row of banner-tablets dividing the said two face portions with the ball-seat in the middle of the said row and a receiving-pocket portion below the said inclined middle face, substantially as described.
15. 3. A game-table having an inclined portion with a series of staggered pins distributed over its surface and projecting upwardly therefrom, and a lower horizontal portion with a series of shallow and numbered ball-pockets within which the balls come to rest after rolling down through the said series of staggered pins, substantially as described.
20. 4. A game-table having scoring devices, an inclined middle portion with a series of staggered pins projecting from its face, an inclosed ball-passage extending longitudinally of the said inclined middle portion and to one side of the series of staggered pins, and an inclined upper portion slanting in the same direction as the said middle portion on a lesser angle of inclination, the said inclined upper portion communicating with both of the said two parts of the said inclined middle portion, substantially as described.
25. 5. A game-table having a receiving-pocket portion, an inclined middle portion with a series of staggered pins projecting from its face, an inclosed ball-passage extending longitudinally of the said inclined middle portion at one side of the said series of staggered pins, an upper portion of the table above the said series of staggered pins and ball-passage and a series of numbered banner-tablets dividing the series of staggered pins from the said upper portion and extending from the upper end of the said ball-passage to the side of the table opposite the said passage, substantially as described.
30. 6. A game-table having a lower horizontal table portion with a series of numbered ball-pockets on its face, an intermediate inclined table portion having an inclosed ball-passage at one side and a series of staggered pins projecting from its upper face outside of the said ball-passage, and an upper inclined table portion at a lesser angle of inclination than the said intermediate portion and of a semicircu-

lar form, the said ball-passage leading to the said semicircular and lesser inclined upper table portion, substantially as described.

7. A game-table having an inclined middle portion, and a series of staggered pins projecting from the face of the said middle portion, one of the pins of the said series being hinged and connected with signaling devices, substantially as described.

8. A game-table having an inclined middle portion, a series of rigid pins projecting upwardly from the face of the said portion, and a hinged pin arranged within the said series and also standing up from the face of the said inclined portion, the said hinged pin being connected with signaling devices, substantially as described.

9. A game-table having on its face a series of staggered pins projecting upwardly, a hinged pin constituting one of the said series of staggered pins and also projecting upwardly from the said table and a bell underneath the said table and connected with the said hinged pin, substantially as described.

10. A game-table having an inclined middle portion, and a series of hinged and rigid pins projecting upwardly therefrom, the said pins being arranged in a staggered form with the hinged pins standing in position with the rigid pins to give the said staggered form, and the said hinged pin being connected with signaling devices, substantially as described.

11. A game-table having a series of staggered pins projecting from its face, and a hinged pin connected with a bell and arranged within the said series of staggered pins to form a continuation of the said series, substantially as described.

12. A game-table having scoring devices, an inclined middle table portion with an inclosed ball-passage at one side thereof, an upper inclined table portion into which the said ball-passage leads, the inclination of the said upper table portion being at a lesser angle than that of the said inclined middle portion, a series of pins extending transversely near the junction of the said two differently-inclined table portions, a seat for a spot-ball between the two middle pins in the said series and banner-tablets hung between the other pins of the said series, substantially as described.

13. A game-table having a lower end portion with a numbered series of shallow ball-pockets for the ball to rest in, an intermediate inclined portion having a series of staggered pins, an upper end portion above the said series of staggered pins, a series of numbered swinging tablets between the said upper and intermediate portions with an open space in the middle of the said tablets and a spot-ball seat within the said open space, substantially as described.

14. A game-table having a lower horizontal portion with a numbered series of shallow ball-pockets for the ball to come to rest in, an intermediate inclined portion having a pro-

jecting series of staggered pins, an upper end table portion above the said intermediate incline and an inclosed ball-passage on one side connecting at its upper and lower ends with 5 the said upper and lower table portions, while the said intermediate inclined table portion is separated from the said ball-passage, substantially as described.

15. A game-table having the intermediate 10 inclined table-face, a lower horizontal face provided with a series of staggered pins, having a series of numbered ball-pockets for the ball to come to a rest in, a semicircular guard 9, at that side of the series of ball-pockets 15 that is farthest from the said inclined table-face and a small central deflector 11, at the middle of the said guard, substantially as described.

16. A game-table having at one side an 20 inclosed and inclined ball-passage for shooting a ball upwardly therethrough, an upper table-face at the upper end of the said ball-passage for the ball to change its course upon, an intermediate inclined table-face having a series 25 of staggered pins slanting downwardly from the said upper table-face for the ball to roll down, the side edges of the said intermediate table-face being parallel, a horizontal lower table-face having pockets for the ball 30 to come to a rest upon, the said horizontal face being of a semicircular form with its curved sides meeting the said parallel sides of the said intermediate inclined table-face and a guard with central deflector at the 35 curved edge of the said lower table-face, substantially as described.

17. In a game-table, the lower horizontal 40 table-face having a series of numbered ball-pockets for the ball to come to a rest in, a guard extending in substantially a semicircle around that side of the said face that is near-

est to the end of the table, and a triangular deflector 11, at the middle of the said guard to prevent the ball from following the curve of the said guard, substantially as described. 45

18. A game-table having at one side an inclosed and inclined ball-passage for having a ball shot upwardly therethrough, an upper table-face at the upper end of the said ball-passage for the ball to change its course upon, 50 an intermediate inclined table-face slanting downwardly from the said upper face for the ball to roll down, the said intermediate face having a series of staggered pins, a horizontal lower table-face having a series of numbered ball-pockets for the ball to come to a rest in, and a semicircular guard and central deflector on that side of the said series of ball-pockets that is farthest from the said 55 upper table-face, substantially as described. 60

19. A game-table having at one side an inclosed and inclined ball-passage for having a ball shot upwardly therethrough, an upper and very slightly-inclined table-face for the ball to change its course upon, a seat for a 65 spot-ball in the middle portion of the board near the junction of the said upper face with the intermediate inclined table-face, a series of banner-tablets extending laterally on each side of the said spot-ball seat, an intermediate inclined table-face for the ball to roll down and accelerate its speed, a series of staggered pins on the said intermediate face to prevent too great an acceleration of the downwardly-rolling ball, and a lower horizontal table-face having a series of shallow ball-pockets for the balls to come to a rest in, 70 substantially as described. 75
